UNITED STATES PATENT OFFICE.

FREDERICK A. KOLSTER, OF PALO ALTO, CALIFORNIA, ASSIGNOR TO FEDERAL TELEGRAPH COMPANY, OF SAN FRANCISCO, CALIFORNIA, A CORPORATION OF CALIFORNIA.

LOOP ANTENNA.

Application filed September 8, 1926. Serial No. 134,216.

This invention relates generally to antennae for effecting a transfer of radio energy between an electrical circuit and an absorption medium.

5 In directive radio reception such as employed in radio compass systems, it is common practice to make use of antennae comprising a lumped inductance which may be rotated to bring its plane in any desired direction. In making radio compass installations upon ships, the loop antenna is placed in an exposed position where it is subjected to severe climatic conditions. Such antennae must have not only high electrical 10 efficiency but must be impervious to moisture and have great mechanical strength.

It is an object of this invention to devise an encased or shielded loop antenna which will have high mechanical strength and low 15 wind resistance.

It is a further object of this invention to devise a loop antenna which will be inclosed in a metal shield or casing but which will have high electrical efficiency.

20 Further objects of this invention will appear from the following description in which I have set forth the preferred embodiment of my invention. It is to be understood that various modifications may 25 be made within the scope of the appended claims and within a range of equivalents consistent with the prior art.

Referring to the drawings:

Figure 1 is a side elevational view showing a loop antenna constructed in accordance with this invention.

Fig. 2 is a detail showing a modification of the invention shown in Fig. 1.

Fig. 3 is a diagrammatical view illustrating the electrical connections to the loop conductors and metal casing.

The invention comprises generally a metal shield or casing constructed in the form of a flat loop and within which one or more 45 antenna conductors are wound. The ends of the metal casing are insulated from direct electrical contact with each other and are electrically associated with the antenna conductor so that the casing forms a part of 50 the antenna inductance. Thus referring to the drawings there is shown a hollow metal casing 10 which is bent in the form of a relatively flat loop. This casing may be constructed of any suitable material having

high electrical conductivity such as copper, 55 and is preferably tubular in shape. The ends 11 and 12 of the casing are preferably insulated from direct electrical contact with each other as by means of a sleeve 13 of insulating material. For rotatably supporting the casing in a vertical plane, the tube has been shown as mounted upon a hollow shaft 14, this shaft being journaled within a suitable bearing 15. The ends 11 and 12 of the casing are preferably arranged so 60 that they are disposed symmetrical with respect to the axis of rotation 16.

In order to form the antenna inductance, one or more conductors are wound within the continuous passageway 18 provided by 70 the interior of the casing 10. Thus there is shown an insulated conductor 19 which is looped a number of times within the casing 10, the terminals 20 being extended through the hollow shaft 14 for making 75 connection with a receiving or signaling circuit. While the arrangement so far described would operate as an antenna, its electrical efficiency would be impaired by the presence of the metal casing 10. In 80 order to increase the electrical efficiency the metal casing 10 is made a part of the antenna inductance. Thus one of the intermediate turns of the conductor 19 is interrupted and the metal casing 10 inserted in series 85 with the same so that the casing forms one loop of the antenna inductance. These electrical connections to the metal casing 10 have been indicated at 21 and 22 and are 90 preferably made adjacent the ends of the casing.

A slightly modified construction has been shown in Fig. 2 in which the ends of the metal casing 10 have been positioned at the bottom of the loop, as for example by incorporating it in the mounting of the casing upon the rotatable shaft 14. In this case the ends of the casing 10 are shown as mounted within an insulating sleeve or block 25 which is secured to the rotatable shaft 14. As in 100 the case of the loop previously described the casing is inserted in series with the antenna inductance as indicated by the electrical connections 21 and 22.

In Fig. 3 the electrical connections of the 105 antenna have been illustrated diagrammatically. As indicated, the loops or turns of the antenna conductor 19 upon either side of

the series connection with the casing 10 are preferably equal so that the casing forms the central portion of the antenna inductance. The casing may also be grounded intermediate its ends as indicated at 28. The terminal wires 20 are connected with the electrical apparatus commonly associated with such antennae as is well known in the radio art. Suitable means such as a variable condenser 29 is generally shunted across the loop in order to bring the same in resonance to the desired signal frequency. The antenna is of course directional in the direction of the plane of the loop.

15 While the device has been described with reference to radio compasses, it is of course applicable for use in other radio systems, both for reception and transmission of radio energy. The metal casing serves to provide 20 a rugged frame work having a minimum of wind resistance and which effectively protects the antenna conductor against climatic conditions.

I claim:

- 25 1. An antenna of the class described comprising an elongated metal casing in the form of a loop, the ends of said casing being insulated from direct electrical contact with each other, and conductors looped within 30 said casing to form an inductance.
2. An antenna of the class described comprising an elongated metal casing in the form of a loop, and a conductor wound with-

in said casing to form an inductance, said conductor being electrically connected with the casing whereby the casing is incorporated as one loop of the inductance.

3. An antenna of the class described comprising an elongated metal casing in the form of a loop, and a conductor wound within said casing to form an inductance, an intermediate portion of said conductor being electrically connected with the casing whereby the casing forms an intermediate loop of said inductance.

4. An antenna of the class described comprising a tubular metal casing in the form of a flat loop, the ends of said loop being insulated from direct electrical contact with each other, an insulated conductor wound within the interior of the casing to form an inductance, the intermediate portion of the conductor being electrically connected in series with said casing whereby the casing forms one of the intermediate turns of the inductance, and means for rotatably supporting said casing.

5. An antenna of the class described comprising a looped conductor, and a metal casing enclosing said loop, said casing being electrically connected with said conductor whereby the casing is incorporated as one loop of the antenna.

In testimony whereof, I have hereunto set my hand.

FREDERICK A. KOLSTER.
